[57] **CLAIM**

The ornamental design for the document sheet with apertures for cards, as shown and described.

DESCRIPTION

FIG. 1 is a top plan view of a document sheet with aperture for cards showing my new design;

FIG. 2 is a front elevational view thereof;

FIG. 3 is a left side elevational view thereof;

FIG. 4 is a right side elevational view thereof;

FIG. 5 is a bottom plan view thereof;

FIG. 6 is a rear elevational view thereof;

FIG. 7 is a cross-sectional view thereof, taken along line 7—7 in FIG. 2;

FIG. 8 is an orthographic projection thereof;

FIG. 9 is a front elevational view of a second embodiment thereof;

FIG. 10 is a rear elevational view of the second embodiment thereof;

FIG. 11 is a front elevational view of a third embodiment thereof; and,

FIG. 12 is a rear elevational view of the third embodiment thereof.

FIG. 1.FIG. 3.FIG. 2.
